DESIGN FOR A GLASS CELERY TRAY OR ARTICLE OF SIMILAR NATURE

T. Clarence Heisey, Newark, Ohio, assignor to A. H. Heisey & Company, Newark, Ohio, a corporation of Ohio

Application April 1, 1939, Serial No. 83,983

Term of patent 14 years

To all whom it may concern:

Be it known that I, T. Clarence Heisey, a citizen of the United States of America, residing at Newark, in the county of Licking and State of Ohio, have invented a new, original, and ornamental Design for a Glass Celery Tray or Article of Similar Nature, of which the following is the specification, reference being had to the accompanying drawing, forming a part thereof.

Figure 1 is a perspective view of a glass celery tray showing my new design.

Figure 2 is a top plan view of the article of Figure 1.

Figure 3 is a transverse sectional view taken on line 3—3 of Figure 2.

Figure 4 is a longitudinal sectional view taken on line 4—4 of Figure 2.

I claim:

The ornamental design for a glass celery tray or article of similar nature, substantially as shown.

T. CLARENCE HEISEY.
